UNITED STATES PATENT OFFICE.

WILLIAM HENRY BEEHLER, OF BALTIMORE, MARYLAND.

EMBROIDERING PROCESS.

1,233,018.

Specification of Letters Patent. Patented July 10, 1917.

No Drawing.

Application filed December 8, 1913. Serial No. 805,473.

To all whom it may concern:

Be it known that I, WILLIAM HENRY BEEHLER, a citizen of the United States, and resident of Baltimore, in the State of Maryland, have invented a certain new and useful Embroidering Process, of which the following is a specification.

My invention relates to a process of embroidery, which is particularly adapted to placing names and addresses on umbrellas and like articles, although, of course, the process is not limited to any particular application.

In working names of purchasers on umbrellas, it is frequently desired to have the name or the name and address, which will all be identified for convenience as the design, easily legible from the inside of the umbrella, so that when the umbrella is opened for use any user will easily see and read the design. It is also undesirable to have it visible from the outside of the umbrella to avoid attracting attention. Therefore, the design should appear on the inside 25 in a color contrasting with the fabric of the umbrella cover and on the outside the design should not be visible at all except by, perhaps, the closest inspection.

To carry out this result the design should 30 either be worked in thread contrasting with the color of the cover and then this thread should be colored on the outside of the cover to correspond with the cover, or else in some cases it may be desirable to work 35 the design in white and then color the outside to correspond with the cover and then apply on the inside some color other than white, and also different from the cover color.

40 My process is particularly designed to carry out the above-mentioned objects in a very economical and practical manner.

The process consists in first dipping into a weak solution of sulfuric acid, some suitable fabric to be used for patterns. Cheese-cloth or cambric, or other light or thin cloth, or a suitable kind of paper, is a suitable fabric for the patterns. After this fabric is dipped in the acid it is dried and 45 is then ready for use. The pattern may be traced upon a piece of this fabric or else in some cases where the embroiderer is expert the fabric may simply be used as a protective device and need not bear an actual 50 pattern, the operator simply placing the fabric upon the umbrella cover and stitch-

ing through both. With the pattern fabric in place, the embroidery is performed by hand or by machine. The embroidery is done, for example, upon a black umbrella 60 cover with a black thread, the pattern or protecting fabric being in this case placed on the inside of the cover. Suitable coloring matter, for instance a good quality of printers' ink of a color to contrast with the 65 cover, for example bright red, is then rubbed upon the design over the pattern fabric which protects the umbrella cover and causes the color to be applied only to the threads constituting the design as they appear 70 through the protecting fabric. Heat is then applied, conveniently by means of a hot iron, over the fabric. This heating performs the double function of fixing the color upon the design thread, and it also disintegrates 75 or decomposes the protecting fabric by reason of its previous impregnation with acid. The pattern or protecting fabric can then be easily rubbed and brushed away, leaving the design clean and clearly outlined in a 80 color sharply contrasting with the umbrella cover.

According to a previously suggested process, the pattern or protecting fabric has consisted of paper without previous treatment 85 and this could only be removed from the complete design by laboriously picking the paper out from between the threads of the design. The present process thus avoids great trouble and expense incident to the 90 old process. Variations of the process consist in applying the protecting fabric to the outside of the cover and stitching the design in a thread or color contrasting with the umbrella cover and then coloring the 95 outside of the design over the protecting fabric, to correspond with the color of the cover. In some cases where it might be desirable, the fabric can be used on both sides of the cover. In all these cases, upon completion of the design, the fabric would be heated to disintegrate it and facilitate its removal.

The fabric constituting the cover of an umbrella or the like on which a name or address is to be embroidered by the above-described process is hereinafter identified in the claims as a main or body fabric to clearly distinguish it from the previously treated pattern or protecting fabric, which is identified in the claims as a pattern fabric, protecting fabric, or previously-treated fabric.

I claim:—

1. The hereindescribed process consisting in applying to a body fabric a fabric which has been treated so that it will more readily disintegrate upon the application of heat, embroidering through the two fabrics, applying color to the embroidery over the previously treated fabric, and then applying heat to facilitate removal of the treated fabric.
2. The hereindescribed process consisting in chemically treating a fabric to make it more readily disintegrate upon the application of heat, applying the treated fabric to the body fabric, embroidering characters in outline through the two fabrics, applying the color to the embroidered outline over the treated fabric, and then heating the treated fabric to disintegrate it and facilitate its removal.
3. The described process consisting in immersing suitable fabric in acid solution to make it more readily disintegrate upon the application of heat, drying it, applying it to a body fabric, embroidering through the two fabrics, applying color over the treated fabric, and then applying heat to fix the color and disintegrate the fabric to facilitate its removal.
4. The described process consisting in chemically treating and drying protecting fabric to make it more readily disintegrate upon the application of heat, applying it to

a ground fabric, embroidering characters in outline through the two fabrics, applying color to the embroidered outline over the protecting fabric and then heating the protecting fabric to disintegrate it and facilitate its removal.

5. The described process of applying identifying characters to an umbrella cover, consisting in applying to the cover fabric which has been previously treated to cause it to disintegrate readily upon the application of heat, embroidering characters in outline through the cover and protecting fabric, applying color to the embroidery outline over the protecting fabric, and then applying heat to the treated fabric to facilitate its removal.

6. The described process of applying identifying characters to an umbrella cover, consisting in applying to the cover fabric which has been previously treated to cause it to disintegrate readily upon the application of heat, embroidering characters in outline through the cover and protecting fabric, applying color to the embroidered outline over the protecting fabric to produce a sharply contrasting color between the said outline and the cover on one side thereof, and then applying heat to disintegrate the treated fabric and facilitate its removal.

WILLIAM HENRY BEEHLER.
